FOLDING MACHINE

Walter E. Naugler, Beverly, Mass., assignor to
 United Shoe Machinery Corporation, Paterson,
 N. J., a corporation of New Jersey

Application August 17, 1932, Serial No. 629,181

71 Claims.

(Cl. 12—54)

It is customary in the manufacture of shoes to cement the margins of certain parts of the uppers and then to fold these margins so as to produce edges of pleasing appearance in the finished shoes.

5 Hitherto machines for performing this and similar operations have commonly fed the work intermittently, the fold being formed preparatory to being pressed by a folder of some kind which operates during the pauses in the intermittent feed 10 movements of the work.

With a view to speeding up the operation of folding machines and at the same time of improving the character of the output, there is provided, according to one feature of the invention, 15 means for feeding the work continuously and a folder which is moved in a path at an angle to the direction of feed movement of the work to form the fold. In the illustrated machine the work is fed continuously by mechanism including two feed members which engage the work in turn 20 one after the other. The folder moves back and forth in the line of feed, and during its forward movement also moves transversely of the line of feed to form a fold in the moving work.

25 According to another feature of the invention, one of the feed members engages the margin of the work, which has been operated upon by the folder, to press or hammer the fold and thus acts as a fold-presser or hammer in addition to its feeding function. In the illustrated machine, one 30 of the feed members engages the body portion of the work adjacent to the folder and cooperates with the folder to form the fold, the other feed member having a work-engaging face which is 35 brought down upon the fold to press it.

In machines which employ a creaser or fold-guide, it is desirable to cause the margin of the work to be drawn tightly about and pressed against the edge of the creaser. According to another 40 feature of the invention, there is provided a folder mounted for movement upon a member which is itself moved in a predetermined path during the movement of the folder with respect to it to accomplish the desired result. In the illustrated 45 construction, the folder is mounted for swinging movement upon a carrier which is moved up and down during the swinging movement of the folder to cause the axis about which the folder swings to move in a predetermined path, whereby 50 an exceedingly effective movement of the folder results.

These and other features of the invention including certain details of construction and combinations of parts will be described as embodied in 55

an illustrated machine and pointed out in the appended claims.

Referring now to the accompanying drawings, Fig. 1 is a front elevation of a machine in which the present invention is embodied.

Fig. 2 is a front elevation of a portion of the machine, the work-supporting table and the housing for the mechanism at the outer end of the lower arm, both having been removed.

Fig. 3 is an end elevation of the parts shown in Fig. 2, the cover plate at the outer end of the upper overhanging arm having been removed,

Fig. 4 is a section on the line IV—IV of Fig. 2,

Fig. 5 is a plan of the work-engaging parts showing a piece of work in process of being operated upon,

Fig. 6 is a perspective of the mechanism for operating the fold-presser carrier and for vibrating the knife, certain parts having been shown in separated relation,

Fig. 6a is a detail of the mounting of the finger which cooperates with the gage,

Fig. 7 is a perspective showing principally the mounting of the creaser,

Fig. 8 is a perspective of the mechanism for operating the creaser carrier, which carries not only the creaser but the knife, the gage and the finger which cooperates with the gage, some of said parts having been shown in separated relation,

Fig. 9 is a detail principally in plan showing the mounting of the knife,

Fig. 10 is a detail in perspective of one of the parts of the mechanism which operates the fold-presser carrier,

Fig. 11 is a perspective of the mechanism for operating the feed-block carrier,

Fig. 12 is a perspective of the mechanism for operating the anvil carrier,

Fig. 13 is a perspective of the mechanism for adjusting certain parts of the machine so as to vary the rate of feed of the work,

Fig. 14 is a perspective of the mechanism for operating the folder,

Fig. 15 is a section on the line XV—XV of Fig. 1,

Fig. 16 is a perspective of one member of the folder-operating mechanism.

Fig. 17 is a view principally in elevation showing the mounting of the folder,

Figs. 18, 19 and 20 are details in elevation showing successive positions occupied by the folder, and

Figs. 21 and 22 are diagrams illustrating the operation of the feed members.

Before proceeding to a detailed description of the machine, a brief general description of its

construction and mode of operation will be given. The machine comprises two pairs of feed members which engage the work in turn one pair after the other in such manner as to feed the work continuously. The upper member of one pair of feed members serves also as a fold-guide or creaser over an edge of which a moving folder bends the margin of the work to form the fold; and the upper member of the other pair of feed members serves also as a hammer or fold-presser to press the fold. The work, as it is fed through the machine, first encounters a gage against which the work is pressed and the margin of the work turned up as far as permitted by a limiting horizontal projection on the gage, which engages the edge of the upwardly turned margin, said upturned margin being held against the curved face of the gage by a cooperating finger. Next, the upwardly turned margin is slit or snipped, if desired, by a snipping knife which is normally inoperative but may be rendered operative when desired. The folder then bends the margin about the thin lower edge of the creaser, which, as has been explained, acts also as the upper one of one pair of feed members, to form the fold; and finally the fold-presser, which, as has been explained, acts also as the upper one of the other pair of feed members, presses the fold. A feed block beneath the work cooperates with the creaser, and an anvil, which is also beneath the work cooperates with the fold-presser. The gage and its cooperating finger, the folder and the knife all move forward and back in the line of feed of the work, the folder and the knife making their folding and their cutting movements respectively transversely of the line of feed while they are temporarily moving forward with the continuously moving work.

Referring now more particularly to Fig. 5, a piece of work 100, such as a part of the upper of a boot or shoe is shown in process of being operated upon. The work at the moment is being gripped and fed forward in the direction indicated by the arrow by the first pair of feed members, a block 19 beneath the work and a creaser 21 above the work. A portion 200 of the cement-coated margin of the work has been turned up by engagement with the upwardly-curved face of a gage 23, being held against the gage by a cooperating finger 25; and part of this upturned margin is about to be bent over the thin lower edge of the creaser 21 by the folder 27 to form a fold. A part 300 of the margin has already been previously folded by the folder and pressed flat against an anvil 29, which forms the lower feed member of the other pair, by a hammer or fold-presser, not shown in this figure but shown at 31 in Fig. 2, which forms the upper feed member of the other pair. The knife 33 is in inoperative position above the work. The block 19, the creaser 21, the gage 23, the finger 25, the knife 33 and the folder 27 are all temporarily moving with the work, while the anvil 29 and the fold-presser 31, which are in separated relation as shown in Fig. 3, are moving back preparatory to gripping the work and feeding it forward. The two pairs of feed members are always moving forward when they grip the work, and each pair grips the work while it is being moved forward by the other pair so that the work is fed continuously through the machine. The anvil 29 moves back and forth in a horizontal path, while the cooperating fold-presser 31 moves into and out 75 of contact with the upper face of the work in

a path which is a flattened ellipse. Of the other two feed members, the creaser 21 moves back and forth in a substantially horizontal path, while the block 19 moves into and out of contact with the under face of the work in a flattened elliptical path. 5

Referring now to Fig. 1 wherein the whole machine is shown in elevation from that side at which the operator sits, the frame of the machine comprises a base A adapted to rest upon a bench, a work-supporting or lower arm B in the outer end of which is located most of the mechanism for operating the feed-block, the folder and the anvil, and an upper, overhanging arm D at the outer end of which is located most of the mechanism for operating the gage, the creaser-foot, the knife and the hammer or fold-presser, said head having a cover plate E which holds the moving parts of the mechanism in place and is fastened by screws F to the arm. The work-supporting arm B has fastened to it by screws, two of which are shown at G, a flat table H upon which the work 100 rests as it passes through the machine, said table having integral with it a housing I which encloses the mechanism at the outer end of the arm B and holds a supply of oil which may be drained off, when desired, by removing a drain plug J. 20

Referring first to Fig. 3, the mounting and mode of actuating the hammer or fold-presser 31 30 will be described first. The upwardly extending stem of the fold-presser is fastened by a screw 35 to a flat face at the lower end of a rod 37 which is vertically slidable through a bore in a lug 39, said lug being integral with the lower end of a 35 swinging carrier 41. Another lug 40 at the top of the carrier has a vertical bore in alignment with the bore in the lower lug 39 and has slidably mounted therein a rod 43 into the lower end 40 of which the upper end of the rod 37 is threaded. The upper end of the carrier 41 is extended laterally to provide a hanger 41a, shaped like a similar hanger 41b (Fig. 2), and by which the carrier is pivotally supported on a pin 61 threaded at the top of the machine in the end of the 45 arm D of the frame as is a similar pin 61' shown in Fig. 2. The end faces of the hangers 41a and 41b abut the end face of the arm D. Threaded upon the upper reduced end of the rod 43 is an 50 adjusting nut 45; and above that is a check-nut 47, there being a heavy compression spring 49 between the lower face of the nut 45 and a shoulder on the rod 43. The rod 37 is prevented from rotating by means of a key 51 which engages a vertical slot in the lug 39. The fold-presser carrier 41 has mounted upon it a channeled slide 52 having a cover and a lateral lug 53 provided with a bore in alignment with the bores in the lugs 39 and 40 through which the rod 37 is also slidable. Between the lower face of this lug and a nut 55 on the rod 37 is a compression spring 57 the tension of which may be varied by turning the nut. The tension of this spring determines the force which is applied to the work by the fold-presser. Between the upper face of this lug 53 and the lower end of the rod 43 is a heavy compression spring 59 through which the fold-presser is raised in a manner presently to be described. The above described mounting of the carrier 41 provides for a 60 swinging movement thereof about the stationary pivot pin 61, thereby to move the fold-presser forward and back in the line of feed of the work; and the fold-presser is moved up and down by the lug 53 through the spring 59 as has been de- 70 75 80 85 90 95 98 99 100

scribed. When it is moved down, the spring 57 is compressed more or less. The limit of downward movement of the rod 37 and the fold-presser is determined by the heavy spring 49 which acts as a stop so that, when there is no work in the machine, the fold-presser will not strike the anvil 29. The fold-presser can be adjusted up and down by turning the rod 43 down on to the upper end of the rod 37; and this can be accomplished by turning the check-nut 47 after it has been screwed down hard against the adjusting nut 45. The swinging of the fold-presser about the pivot 61 and its up-and-down movements are so timed that the fold-presser moves in a generally elliptical path in which it descends upon the work, moves to the left with the anvil 29, and then rises and returns to initial position.

The upward and downward components of the movement of the fold-presser are produced as has been explained by the up-and-down movements of the slide 52 on the carrier 41, the movements of the slide being caused by a crank pin 65 on the end of a rotary shaft 63. This crank pin extends into a bore 67 (Fig. 4) in a block 69 in the form of a cross, the horizontal bar of which is received between two horizontal flanges 52a and 52aa (Fig. 4) which project from the rear of the slide 52. Thus when the shaft 63 is rotated, the slide 52 is moved up and down. The driving shaft 63 and its pin 65 are shown clearly in Fig. 6 in spaced relation from the block 69. The lateral component of the movement of the fold-presser is caused by this same crank pin 65 as it acts also to swing a bell crank lever 71 (Fig. 6) about a fixed rod 73. This rod 73, which is headed at its outer end, has a cylindrical shank received in a bore in the frame D and held there by a set screw, such as the set screw 73a shown in Fig. 2 for a corresponding rod 73'. The upright arm of the bell crank lever 71 has a round hole through its upper part and two segmental flanges 75 (Fig. 4) projecting from the rim of the hole to receive a member 77 (Fig. 10), said member having a vertical groove 79 to receive slidably the upright bar of the cross 69, and a vertical slot 81 through which the crank pin 65 extends. Consequently, rotation of the shaft 63 and its crank pin 65 swings the bell crank lever 71 as has been stated. The lever 71 has a horizontal arm, extending to the right in Fig. 6, which has a bore to receive a pin 83 projecting from the upper end of a vertical link 85, the lower end of which has a pin 87. The bell crank 71 also has integral therewith, and extending to the left in Fig. 6, a knife actuator arm 186, the function of which will be later described. A link 89 having an elongated hub 89a pivoted on a normally fixed but adjustable pin 91 carries at its outer end a pivot pin 93; and the inner end or head of a link 97 has two elongated sockets to receive respectively the pin 87 on the link 85 and the pin 93 on the link 89. This link 97 at its outer end carries a pin 99 which is received in a bore in the lower part of the carrier 41 as best shown in Fig. 3. The fixed but adjustable pivot pin 91 (Fig. 6) is carried by an arm 101 fast to the outer end of a shaft 103 which may be turned to move the pin 91 into and hold it in various adjusted positions. Assuming that this pin 91 is held stationary in a position in which its axis does not coincide with the axis of the pin 99, rocking of the bell crank lever 71 about the pivot pin 73 moves the link 85 up and down; and this movement, transmitted through the pin 87 to the head of the link 97,

causes the latter to turn on the pin 93 carried by the swinging link 89 which rocks about the fixed pivot 91. The rocking of the link 89 causes the link 97 to oscillate in a path determined by the location of the axis of the pin 91 so that the pin 99 moves laterally and imparts oscillation to the carrier 41 (Fig. 3) about its pivot 61. If the axes of the pin 91 and the pin 99 are in alignment, substantially no lateral oscillation will be imparted to the pin 99 and no oscillatory movement to the fold-presser carrier 41; and the extent to which the carrier 41 is oscillated depends upon the position into which the pin 91 is adjusted by adjusting the shaft 103.

As has been stated above the creaser-foot, the combined gage and cutting block and the knife all move back and forth in the line of feed movement of the work. These parts are all carried directly or indirectly by a carrier 41' (Fig. 3) similar to the carrier 41. A vertical rod 105, which as will be presently described carries the creaser-foot 21, is vertically slidable in aligned bores formed in lugs on the carrier 41', being normally held down by a compression spring 107 located between the upper lug and a collar 109 adjustably fastened to the rod by a set-screw 111, the downward movement of the rod being limited by an adjusting nut 113 threaded upon the upper end of the rod. Vertically slidable on the carrier 41' is a channeled slide member 115 which is similar to the slide member 52 on the carrier 41; but the slide member 115 has no lug in engagement with the rod 105 since it is not desired to impart any vertical movement of the slide member to said rod. The slide member 115 has rearwardly projecting spaced flanges 115aa and 115a (Figs. 2 and 4) which receive the horizontal bar of the cross 69'. The carrier 41' is swung about a fixed pivot 61' at the top of the machine, which corresponds to the pivot 61 of the other carrier, by a mechanism (shown partly exploded in Fig. 8) which is just like the mechanism shown in Fig. 6 for swinging the fold-presser carrier 41, except that these two mechanisms are respectively a right-hand and a left-hand mechanism. It is believed to be unnecessary to describe in detail the mechanism shown in Fig. 8 for swinging the carrier 41' about its pivot. Each of the elements in this figure has been given the same reference numeral as the corresponding element in Fig. 6, but each has been marked with a prime. Rotation of the shaft 63' with its crank-pin 65' rocks the bell crank lever 71' about the rod 73' and swings the horizontal arm of the bell crank lever 71' up and down. This moves the vertical link 85' up and down, and rocks the link 97' about the swinging pin 93' on the link 89' which itself swings about the fixed but adjustable pivot 91'. This imparts a lateral movement to the link 97' so that the pin 99' oscillates the carrier 41' (Fig. 3) about its pivot 61'. Here again, the position in which the pivot pin 91' is held determines the extent of oscillation of the carrier 41'.

The rod 105, which indirectly carries the creaser-foot 21, passes down through a bore in a block 117 (Figs. 3 and 7), being fastened to the block by a screw 119, said block having two arms 121 extending to the right and spaced in the direction of the length of the frame arm D. One of these arms is shown in Fig. 3, and both of them are shown in Figs 2 and 7, said arms having mounted between their outer ends a roll 123. Extending down between one side (Fig. 7) of the block 117 and the roll 123 is a depending portion 75

of the carrier 41' which is rectangular in cross-section, said portion serving as a guide when the block 117 is raised or lowered in a manner which will presently be described. The lower portion 5 of the block 117 has a horizontal cylindrical boss in which is rotatably mounted a short shaft 125. In the underside of the block and extending through the cylindrical boss is a slot to receive the hub of the creaser-foot 21, said hub being 10 bored to receive the small shaft 125 and being fastened thereto by a set screw 127. The creaser-foot is normally held in the position shown in Figs. 2 and 7 by a spring-pressed pin 129 carried by a boss 21a at the upper end of the creaser 15 which swings the creaser as far about the axis of the small shaft 125 as is permitted by a stop-screw 131 which engages the lower end of the rod 105. In order to raise the creaser and swing it to the left, as viewed in Figs. 2 and 7, when 20 desired, a small segmental arm 133 has its hub adjustably fastened to one end of the small shaft 125 by a pinch-screw 135, said arm being adapted to contact with a roll 136 which is carried by the downward extension of the carrier 41' so that, 25 when the block 117 is pushed up, the creaser-foot 21 will be moved up and swung out. In order to move the block 117 up, a small lever 137 pivoted at 139 to the frame has at its left-hand end a roll 141 which, when the right-hand end of the 30 lever is pushed down, contacts with the underside of the roll 123 and pushes up the block 117. As the block moves up, the small shaft 125 is rocked and the creaser-foot is moved up and 35 swung out to the left thus withdrawing it from the crease of the work without damage to the latter. By changing the angular position of the segmental arm 133 on the shaft 125, the creaser-foot may be either moved straight up or moved 40 in the manner which has just been described, since no swinging of the creaser-foot will occur until the outer end of the arm 133 has engaged the roll 136.

The knife 33 (Fig. 6) is mounted for vibratory movement on the depending portion of the 45 creaser-carrier 41'. The gage 23, the lower end of one face of which serves as a shear member in cooperation with the knife, is adjustably fastened to this depending portion by a screw-bolt 143. The finger 25 (see also Fig. 6a), which 50 cooperates with the gage, has a bent stem which is slotted at 147 adjustably to receive a bearing pin 144 which is rotatable in a bore in the extension of the carrier 41'. This pin has a reduced threaded end to receive a nut 145, said 55 nut having a flattened hub which extends into the slot 147 in the stem of the finger 25. After the pin has been turned to loosen the nut, the finger may be adjusted horizontally. The gage 23 (Fig. 6) has an overhanging horizontal projection 151 the purpose of which is to limit the extent of the margin of the work which is turned up by the gage. The finger 25 has a flat horizontal face near its forward end which is held 60 against a flat face on the gage by a tension spring 149 connected to an offset inward extension 25a of the finger and to a plate (Fig. 2) on the frame. Returning now to Figs. 6 and 9, the knife 33 is 65 clamped to a block 157 having extending horizontally from it a short hollow shaft 159 which is rotatable in a horizontal bore in the extension of the carrier 41', said shaft being held from longitudinal movement by a nut 161 and a check-nut 163 threaded on the outer end of this hollow 70 shaft. The upper portion of the stem of the knife 75

is received in a dovetailed slot in the block 157 and is clamped in place, as best shown in Fig. 9, by the suitably shaped head 165 of a small rod 165' which extends through the hollow shaft 159 and has threaded on its outer end a nut 167. Extending rearwardly from the block 157 is a pin 169 which is received in a socket in the head of a small T-shaped member 171, the substantially horizontal stem of which passes loosely through a socket formed in a hub at the lower end of a link 173, being held from longitudinal movement by a nut 175 threaded on the outer end of the stem of the member 171. The pin 169, the T-shaped member 171 and the socket at the lower end of the link 173 form in effect a universal joint 15 so that the knife may be moved back and forth in the line of feed with the carrier 41' without disturbing its connection with the link 173, through which the knife is vibrated when it is desired to snip the edge of the work. The upper 20 end of the link 173 is pivoted at 177 to one end of a lever 179, the hub of which is rotatable on the rod 73, and the other end of which has a fork 179a. The lever 179 has a vertical pin 181 about which is pivoted a second lever 183, the farther 25 end of which has a latch in the form of a horizontal extension 185 which is rectangular in cross-section except for two beveled corners. When it is desired to cause the knife to vibrate, this latch 185 is caused to engage a socket in a 30 constantly vibrating actuator arm 186 which is integral with the bell crank lever 71. In the position of parts shown, the lever 183 is being held in such an angular position about the pin 181 35 that the latch 185 is entirely received between the branches of the forked end 179a of the lever 179. The lever 183 is so held by the enlarged head of a push rod 187 which is connected to a treadle rod 189 (Fig. 1). The inner end of the push rod 187 is pivoted at 191 to the upper end of an arm 193 (Fig. 13) the hub of which is fast to a rock-shaft 195. A second arm 196, like the arm 193, 40 also has its hub fast to the rock-shaft and is pivotally connected at its outer end to the treadle rod 189. A tension spring 197, connected at one 45 end to the pivot at the upper end of the arm 196 and at the other end to a pin 199 (Fig. 1) on the frame urges the push rod 187 continually to the left. Returning to Fig. 6, a compression spring 201, located between the lever 179 and the lever 183, tends at all times to swing the lever 183 about the pivot 181 but is not effective until the push rod 187 is withdrawn. Even then it may not be effective instantaneously, depending upon the 50 position of the vibrating actuator 186. The construction is such that the latch 185 on the end of the lever 183 is in alignment with the socket in the actuator 186 when that member is reversing the direction of its movement at the top 55 of its stroke and is thus momentarily stationary. A cylindrical stop pin 205a is slotted to receive a screw driver and is supported on an eccentrically placed shank which enters the frame D and is held in adjusted position by a set screw (Fig. 3). The forked end 179a of the lever 179 abuts this 60 stop pin and may thus be located to bring the latch opposite the slot of the actuator 186 when the latter is at the top of its stroke. A vertical rod 203 having its upper end slidable in a bore in 65

a stationary pin 205 held in place in the frame by the head of a screw 207 has a hub at its lower end to receive the pin 177 and carries a compression spring 209 to hold the knife raised when it is not being vibrated. With this construction, therefore, any selected portion of the edge of the work may be snipped by depressing the treadle (not shown) which is attached to the lower end of the treadle rod 189 (Fig. 1).

Referring to Fig. 2, the tail 25a of the finger 25 is urged upward by the spring 149 to hold a portion near the other end of the finger against a flat horizontal face on the gage 23. This tail lies in the downward path of movement of a horizontal pin 213 which is adjustably held in a horizontal slot in a small lever 215 (see also Fig. 7) one end of which is pivoted about the pin 139 and the other end of which extends beneath the creaser-lifting lever 137. A stop-screw 211 threaded through the lever 215 contacts with the frame. Depressing the finger-piece at the outer end of the lever 215 raises the finger 25, and depressing the finger-piece at the outer end of the lever 137 raises the finger 25 and also raises and swings outwardly the creaser 21.

As has been explained, the anvil 29 moves back and forth in a horizontal path in the line of feed movement of the work. The mechanism for producing this movement of the anvil is in principle the same as, and in construction quite similar to, that which actuates the creaser 21. Referring to Fig. 12, the anvil 29 is fast to the top of a carrier 219, said carrier being fastened by a set screw 218 to a horizontal slide rod 220 (Fig. 3) which extends through a bore 222 (Fig. 12) in the carrier, said carrier being held upright and steadied in its sliding movement by a fork at its lower end which fits over a block 221 and slides upon the block. This block (Fig. 14) and another block 221' just like it which, as will presently appear, is engaged by a fork on the lower end of the carrier of the feed-block 19, are loosely mounted respectively upon two hollow trunnions which project horizontally from the hub of a lever 405, later to be described, the hollow trunnions and the hub of the lever being rotatable on a horizontal rod 224 (Fig. 3) carried by the frame. Referring again to Fig. 12, the carrier 219 has a socket to receive an actuating pin 223, corresponding to the pins 99 and 99' which oscillate respectively the fold-presser carrier 41 and the creaser-carrier 41', said pin 223 being actuated indirectly from a crank-pin 225 on a driven rotary shaft 227. An elongated hub of a link 229 receives the outer end of this crank-pin, the lower end of the link having a small pivot pin 242. This pin is received in a hollow pivot 231 formed at one end of a link 241, the other end of which carries the pin 223. A link 233 has a hub at one end to receive the hollow pivot 231 and at the other a hub to receive a fixed but adjustable pin 235 carried at the outer end of an arm 237 the inner end of which is fast to a shaft 239. This shaft may be adjusted into various angular positions to change the position of the pin 235 and hold it stationary. If the pin 223 is in line with the fixed but adjustable pivot pin 235, rotation of the shaft 227 will not move the pin 223 bodily, and no movement will be imparted to the anvil 29. If, however, the pin 223 is not in line with the pivot pin 235, the pin 223 will be moved bodily and will move the anvil back and forth, the extent of this movement depending upon the position in which the pivot pin 235 is held.

The feed-block 19 (Fig. 3) which, with the creaser, forms one pair of feed members, moves in an elliptical path substantially like that of the fold-presser 31, except that it engages the underside of the work while the fold-presser 5 engages the upper side. Referring to Fig. 11, the block 19 has a stem the upper part of which is curved and the lower part of which is vertical and slidable in a vertical dove-tailed guideway in a carrier 243. This carrier has a horizontal bore 230 to receive the slide rod 220 (Fig. 3) and is slidable upon this rod instead of being fastened to the rod as is the anvil carrier. At its lower end it has a fork which fits over and slides upon the block 221' (Fig. 2). A coiled compression spring 245 (Fig. 11), located between a lug on the carrier 243 and a lug on the stem of the block 19, encircles a pin 247 fast to the lug on the stem of the feed-block and slidable through a bore in the lug on the carrier. The spring 245 continually urges the block 19 to move up to an extent limited by a nut 249 threaded on the lower end of the pin 247. In order to move the block 19 down at the proper times, a pin 251 carried by the stem of the feed-block 19 is received between the horizontal branches of a fork at the outer end of a lever 253 having an elongated hub rotatable upon a horizontal pin 255 which projects eccentrically from one end of a short shaft 257 rotatable in a bore in the frame B. This shaft has a slot 259 in one end to facilitate turning it and has a middle portion of reduced diameter to receive the thrust of a set screw (Fig. 4), which holds the shaft in adjusted angular position. Turning the shaft 257 changes the position of the pin 255 and thus permits the extent of up-and-down movement of the outer end of the lever, and consequently of the feed-block 19, to be varied. The lever 253 is pushed down at the proper time by an arm 263 the outer end of which engages a roll 264 carried by the lever. This arm is fast to one end of a rock-shaft 265 which is rotatable in a bearing in the carrier 243. The other end is fast to one end of a bent arm 267 having at its other end a fork between the branches of which a square block 269 is slidable, said block having a bore to receive a small crank-pin 271 formed on the outer end of a second crank-pin 273 which in turn is formed on the outer end of a third crank-pin 275 carried by a rotary shaft 271. The first crank-pin 271 imparts to the feed-block 19 the vertical component of its movement. The second crank-pin 273 imparts to the feed-block 19 the lateral component of its movement, and the third crank-pin 275 imparts to the folder a component of its movement which will be later described. The lateral component of the movement of the feed-block 19 is imparted to it by a link mechanism, including a fixed but adjustable pivot which is similar to the three mechanisms described above for imparting lateral movement respectively to the fold-presser, to the creaser and to the anvil. The fixed but adjustable pivot 279 is carried at the outer end of an arm 281, the inner end of which is fast to the end of a shaft 283 (Figs. 2 and 13) which may be adjusted to move the pin 279 into and hold it in various adjusted positions. A link 284 has at one end an elongated hub to receive the pin 273 and at the other end a pin 285 extending into a sleeve 287 integral with one end of a link 289, the other end of which has a pin 291 extending into a bore in a boss on the carrier 243. A link 293 has a bore in one end to receive the sleeve 287 within which is the pin 285 and at the other end a bore 75

- to receive the fixed but adjustable pivot 279. If the last-named pivot and the pin 291 are in line, rotation of the shaft 277 will impart no movement to the carrier 243; but if they are out of line, as shown, rotation of the shaft 277 will move the pivot 291 bodily and impart back-and-forth movement to the carrier 243, the extent of such movement depending upon the position in which the pin 279 is held.
- Referring now to Figs. 14, 16 and 17, the mounting of the folder 27 and its actuating mechanism will be described. The folder is carried indirectly by a rectangular frame comprising two bars 351, 353, the vertical face 351' of the bar 351 being held against a vertical face on the bar 353; and, through the forward ends of these bars (the left-hand ends as viewed in Figs. 14 and 17) passes a rod 355 on which the frame is pivoted for up-and-down swinging movement. One end of the rod 355 has an eccentric trunnion 357 received in a bore in the frame and held in adjusted angular position by a set-screw 359 (Fig. 3). The other end has a second trunnion 361 concentric with the trunnion 357 and provided with a slot to receive a screwdriver. This trunnion 361 is also received in a bore in the frame. By inserting a screwdriver in the slot and turning the rod 355, the folder-carrying frame may be adjusted horizontally to position the folder properly in a direction transverse to the direction of feed movement of the work. Returning to Figs. 14 and 17, the right-hand ends of the bars 351, 353 are bored to receive a shaft 363, and between these rear ends is a hub 365 fastened to the shaft and having pivotally connected to the bottom of it the upper end of a rod 367 which passes down through a bore in a block 369 and has nuts 371 threaded on its lower end, between the upper one of which and the block there is located a compression spring 373. The purpose of the spring is to permit the folder-carrying frame to rock upwardly about the rod 355 at any time when the folder 27 is brought down upon a thick locality of the work, for example upon a back seam. The rod 367 has a collar 375 fast to it and in contact with the top of the block 369. A small pin 377 rigid with the block 369 is fast to the outer end of a horizontal arm 379, the hub of this arm being rotatable on a stationary shaft 381. Another arm 383, integral at its inner end with the same hub, carries at its outer end a pin 385 extending into an elongated bore in the lower end of a link 387, the upper end of which has a bore to receive the inner end of the crank-pin 225 on the shaft 227. It will be recalled that the anvil 29 (Fig. 12) is moved back and forth by movement of this same crank-pin 225. Returning now to Figs. 14 and 17, the rotation of the shaft 227, through the crank-pin 225, the link 387, the pin 385, the arms 383, 379, the block 369 and the vertical rod 367 will swing the folder-carrying frame up and down about the rod 355 and thus raise and lower the folder. This up and down motion moves the carrier bodily in a direction across the line of feed. The vertical hole in the block 369 is slightly larger than the diameter of the rod 367 to prevent these parts from binding.
- The folder 27 is slidably and rotatably mounted on a small horizontal pin 389 (Fig. 17) carried by the middle portion of a bent link 391. This pin 389 is parallel to the line of feed. The hub at one end of this link has fastened in it a small rock-shaft 393 rotatable in alined bores in the depending arms of a yoke-like link 395 (see also

Fig. 16) the upper portion of which has at opposite ends alined trunnions 397 received in alined bores formed horizontally in the bars 351, 353 of the folder-carrying frame. The hub at the other end of the link 391 has fast to it a small rock-shaft 399, the ends of which are received in alined bores in a second yoke-like link 401 having at its upper part alined trunnions 403 which, like the trunnions 397 of the link 395, are also rotatable in alined bores in the folder-carrying frame. The 10 yoke-like link 395 is rocked about its trunnions 397 by means of the previously mentioned lever 405 having projecting horizontally from both sides near its middle portion hollow trunnions 407, 409 rotatable in bores in the square blocks 15 221, 221' upon which the lower forked ends of the anvil carrier 219 (Fig. 12) and the feed-block carrier 243 (Fig. 11) are slidable. The forward end of the lever 405 has an elongated split hub in which is fastened by a pinch-screw 411, a rod 412 having eccentric trunnions 413 which project from both ends of the rod. Pivoted at their lower ends on these projecting trunnions are two links 415, 417, the upper ends of which are pivoted on alined horizontal pins 419, 421 carried by lugs which project in a generally horizontal direction from the yoke-like link 395. The rear end of the lever 405 has a bore to receive the small end of a horizontal pin 423 fastened to it by a nut 425, the larger end of the pin being rotatably received in a bore in the head 427 of a horizontally extending pin 429 (Fig. 2), the head being held in place by a screw 431. The pin 429 is slidable and rotatable in a horizontal socket in a hub 432 at the lower end of a link 433, the hub at the upper end 35 of which has a bore to receive the crank-pin 275 on the end of the shaft 277. This crank-pin 275 is one of those shown in Fig. 11, the other two, 273, 271, serving to operate certain mechanism for imparting movement to the feed-block 19. Referring again to Fig. 2, the right-hand end of the lever 405 has a curved face generated about the axis of the hollow trunnion 407, and this curved face engages a flat vertical face on the left-hand end of the hub 432 so that the distance 45 between this face and the axis of the trunnion remains always the same. The right-hand end of the hub 432 has a raised rim 434 which bears against a vertical face on the frame as the hub 432 moves up and down. Returning now to Fig. 50 14, rotation of the shaft 277 rocks the lever 405 about the alined axes of its trunnions 407, 409 and rocks the yoke-like link 395 back and forth on its trunnions 397. The bent link 391, which carries the folder 27, is pivoted at one end to the 55 yoke-like link 395, at a certain distance from the axis of the trunnion 397, and at the other end, at the same distance from the axis of the trunnion 403, to the yoke-like link 401 and consequently the pin 389 upon which the folder 27 is pivoted is 60 moved bodily to and fro.

It has been explained that the folder-carrying frame is swung up and down about the axis of the rod 355 to raise and lower the folder and that the folder is also moved bodily in a curved path due 65 to the mechanism which has just been described. In addition to these movements, the folder is rocked about the pin 389. To this end, the portion of the folder below the pivot 389 has a horizontal bore to receive a horizontal pin 435 integral with the upper end of a link 437, the lower end of this link having trunnions 436 (see also Fig. 2) which are received in alined bores in the yoke-like link 395 which are below the alined bores in which the trunnions of the link 391 are 75

received. Thus when the yoke-like link 395 is swung back and forth, since the lower end of the link 437 is farther from the axis of movement of the link than the lower forward end of the link 391, the folder is rocked about its pivot 389. The pin 435 extends through the link 391 for a purpose presently to be described, and hence there is provided in the link 391 a curved slot 439 to permit back-and-forth movement of the pin 435. This pin, which is integral with the link 437, has an elongated head 441 which engages the link 391 on the opposite side from the link 437 and keeps the upper end of the link 437 from moving away from the link 391, since such movement would cause the trunnions at the lower end of the link 437 to bind in their sockets. The links 437 and 391 are assembled by holding the link 437 in such a position that the head 441 may be passed through the slot 439 after which the link 437 may be swung into the position shown. By reason of the mechanism which has been described above the folder moves as indicated in Figs. 17 to 20. The folder also moves back and forth in the line of feed, being slidable on its pivot pin 389. To this end a vertical slot (Fig. 14) in the depending portion of the folder 27 receives a thin generally segmental member 443 (Figs. 2 and 11) which is rigid with the carrier of the feed-block 19 and moves back and forth in the line of feed as has been described.

The four rotary shafts which impart movements to the work-engaging parts of the machine, as has been described above, are shown in section in Fig. 15. The shaft 63 moves the fold-presser in a generally elliptical path and also vibrates the knife about its pivot when it is connected with the knife. The shaft 63' moves the creaser, the knife, the gage, and its cooperating finger back and forth in the line of feed. The shaft 227 moves the anvil back and forth and also moves the folder-carrying frame up and down. The shaft 277 moves the feed-block in an elliptical path, moves the link 391 upon which the folder is mounted, rocks the folder about its pivot and moves the folder back and forth in the line of feed.

These four shafts are driven respectively by four shafts, 445, 447, 449 and 451. The shaft 445 has at its forward end a thick disk 453 provided with a groove 455 extending diametrically across its face to receive a rectangular slide-block 457 into which extends a pin 459 carried by an arm 461 having a split hub to receive the shaft 63, said shaft being fastened firmly to the hub by a key 463 and a pinch-screw 465. The rear portion of the shaft 445 has fast to it a small gear 467 which meshes with a large master-gear 469 on a countershaft 471, said large gear being driven by a small gear 473 on the shaft 451 which is the driving shaft of the machine and is rotated continuously from any suitable source of power by means of a belt 475 (Fig. 1). The shaft 447 is driven from the large gear 469 by means of a small gear 477 on said shaft; and similarly the shaft 449 has a small gear 479 which meshes with the large gear 469. The mechanisms which respectively connect the shaft 447 to the shaft 63, the shaft 451 to the shaft 277 and the shaft 449 to the shaft 227 are all like the mechanism, described above, which connects the shaft 445 to the shaft 63; and consequently, these other three mechanisms will not be described in detail.

It has been explained above that the extent of the lateral movement of the fold-presser carrier depends upon the angular position into which

the shaft 103 (Fig. 6) which carries the fixed pivot pin 91 is adjusted, that the extent of the lateral movement of the creaser-carrier depends upon the angular position into which the shaft 103' (Fig. 8) is adjusted, that the extent of the lateral movement of the anvil-carrier depends upon the angular position in which the shaft 239 (Fig. 12) is adjusted, and that the extent of the lateral movement of the feed-block carrier depends upon the angular position in which the shaft 283 (Fig. 11) is adjusted. When these four shafts are adjusted, it is necessary that they should be adjusted simultaneously and to the same extent.

Referring to Fig. 13, wherein the rear ends of these four adjusting shafts are shown, the shaft 103' has fast to its rear end a segmental gear 481 which meshes with a similar segmental gear 483 fast to the rear end of the shaft 103. The gear 483 is formed at one end of a lever 485 pivoted at the other end at 487 to the lower end of a link 489, the upper end of which is pivoted at 491 to the outer end of an arm 493 the hub of which is fast to a rock-shaft 495. Fast also to this rock-shaft is the hub of a lever 497, the outer end of which is pivoted at 499 to the outer end of a short arm 501 the other end of which has integral with it a collar 505 adjustably fastened by a set-screw 503 to a vertical treadle-rod 507 which passes up through a hole in a portion of the frame and has at its upper end a stop-nut 509 and a check-nut 511. The adjustable shafts 239, 283 carry respectively segmental gears 513, 515 which, like the segmental gears 381, 483 mesh with each other. The rear end of the shaft 239 has adjustably fastened to it by a set-screw 517 the hub of an arm 519, the outer end of which is pivoted at 521 to one end of an arm 523 the other end of which has integral with it a collar 527 adjustably fastened by a set-screw 525, to the treadle-rod 507. The lower end of the treadle-rod 507 is connected to the usual treadle, not shown, held up by the usual spring, also not shown, as is the lower end of the treadle-rod 489 of the knife-operating mechanism. The upward movement of the treadle-rod 507 is limited by a stop-screw 529 threaded through a part of the frame and having upon it a check-nut 531. When the treadle-rod is at its uppermost position, as shown in the figure, the four adjusting shafts 103, 103', 239 and 283 are holding their respective pivot pins in positions to produce a minimum feed of the work; and when the treadle-rod is depressed the feed is increased until a maximum is reached at the time the stop-nut 509 strikes the frame.

Referring now to Figs. 17 to 20, four of the positions which the folder passes through in one cycle of its movement are shown. In Fig. 17, the folder has engaged the work, is moving upward and to the left, and is rocking forward. It continues this movement until it reaches the position shown in Fig. 18 in which the margin of the work has been drawn tight and bent over upon the creaser. It then moves upward and to the right to the position shown in Fig. 19. In so doing it rocks backward to cause the corner 535 to rub against the work in the locality of the fold line 200 thus pressing this portion of the work against the thin edge of the creaser. It is this corner which is the last portion of the folder to engage the work, and consequently the release of the work is abrupt so as not to interfere with the continuous feed. From the position shown in Fig. 19, the folder moves downward and to the right and rocks backward into

the position shown in Fig. 20 after which it moves downward to the left and then upward to the left and rocks forward once more into the position shown in Fig. 17. It will thus be noted that 5 the folder approaches the work in a given path and moves away from the work in a path which is not a reversal of its path of approach but is quite a different path designed to cause the folder to engage the work at the last movement over 10 a small locality and to free the work instantly so as to facilitate the continuous feed of the work.

If no up-and-down swinging movement about the rod 355 (Figs. 2 and 17) was imparted to the folder-carrying frame, the folder would merely 15 rock about a fixed axis 537 which would be located a distance from the axis of the moving pivot 389 equal to the distance between the axis of the trunnions 397 of the link 395 and the axis of the rock-shaft 393. Any point on the 20 edge of the folder would then be moved back and forth laterally in an arc centered on 537. Owing, however, to the swinging of the folder-carrying frame about the rod 355, this axis is moved up and down, with the result that a 25 point on the axis 539 about which the folder swings at any given moment is moved in an orbital path indicated by the small dots 541 in a clockwise direction as indicated by the small arrows. The axis 539 is parallel to the line of feed 30 and the orbital path lies in a plane at an angle to the edge of the work. Thus the combination of the up-and-down movement and the rocking movement of the folder causes the folder to move in the manner which has been described above. 35 Although a folder mounted for swinging movement about a pivot pin which is itself moved during the swinging of the folder to cause the folder to move in a particular path has been shown and described, it should be understood that 40 a folder of this general type is not limited to the particular path which has been shown and described nor to use with machines in which the work is fed continuously.

Referring to Figs. 21 and 22, the manner in 45 which the fold-presser and the feed-block respectively engage and disengage the work to feed it continuously will be described. In Fig. 21 the shaft 63 which imparts movement to the fold-presser and the driving shaft 445 for the shaft 50 63 are shown as part of a diagram. The driving shaft 445 is at all times out of line with the shaft 63, being here shown at a predetermined distance below it. Every time the driving shaft 445 rotates through that 180° of its revolution 55 in which the crank-pin 459 (Fig. 15) is above the line 603, the shaft 63 rotates through a greater distance, namely through 180° plus the sum of the two angles included respectively between the lines 601 and 605 and between the 60 lines 601 and 607. Assuming that these two angles are each 20° the shaft 63 rotates through 220°, and the fold-presser is moved a distance which is proportional to the distance from the point P to the point R along the circle 600 in 65 the direction of the arrow. And every time the driving shaft 445 rotates through the 180° in which said crank-pin is below the line 603, the shaft 63 rotates through 140°, and the fold-presser is moved a distance which is proportional 70 to the distance from the point R to the point P along the circle 600. While the fold-presser is moving, so to speak, from the point R to the point P, it feeds the work; and, while it is moving from the point P to the point R, it is out 75 of engagement with the work. Disregarding, for

the present, the increase and decrease in the angular velocity of the shaft 63 due to the manner in which it is driven, the fold-presser has a slow feed movement and a quick return. The fold-presser may thus be considered to engage 5 the work at the point R, to release it at the point P, and to move out of engagement with the work back to the point R. The fold-presser moves forward and back once for each rotation of the shaft 63, and consequently its velocity is 10 zero at two of the angular positions of this shaft. Assuming now that the upper half of the circle represents the backward movement of the fold-presser and that the lower half represents the forward movement, the two points where the line 15 601 intersects the circle are the points where the movement of the fold-presser is reversed. The location of these points depends, of course, upon the relative positions of the crank-pin 459 (Fig. 15) on the rear of the shaft 63 by which 20 it is driven and the crank-pin 65 (Fig. 6) at the front end of the shaft by which said shaft imparts motion to the fold-presser. From this it will appear that the velocity of the fold-presser is increasing at the point R where it engages the 25 work and is decreasing at the point P where it releases the work.

Referring now to Fig. 22, wherein the shaft 277, which imparts movement to the feed-block and the shaft 451 which drives the shaft 277 are 30 shown, these two shafts are the same distance apart as are the shafts 63, 445; and the feed-block engages the work at the point S while its velocity is increasing and releases the work at the point T while its velocity is decreasing. The 35 timing of the rotation of the shafts 63 and 277, however, is such that the fold-presser, moving at decreasing velocity, is releasing the work at the point P when the feed-block, moving at increasing velocity, is engaging the work at the point S. 40 On the other hand, the feed-block, moving at decreasing velocity, is releasing the work at the point T when the fold-presser, moving at increasing velocity, is engaging it at the point R. The work is then fed continuously but not at a uni- 45 form rate of speed.

It has been stated that the cover plate E (Fig. 2) holds in place certain mechanism which is located in the outer end of the overhanging arm D. Referring first to Fig. 3, the creaser foot 21 50 is mounted in the carrier 41' which has a bore in the hanger 41b at its upper end to receive and slip over the pivot pin 61' secured in the outer end of the overhanging arm D and which has at its lower end a second bore to receive the actuating pin 99' by the bodily swinging movement of which the creaser carrier is swung back and forth about the pivot 61'. In Fig. 3, the cover plate E, which, being normally held against 55 movement in the direction of the axes of these pins, holds the carrier 41' thereon, has been removed; and the carrier may be removed from the machine by merely sliding it off the two pins. These two pins are in telescoping relation respectively with the two bores in the creaser carrier 41' when the carrier is in place in the machine and are held in this relation by the cover plate E which contacts with the outer flat faces of two bosses M and N formed on the creaser carrier and shown in Fig. 2. Referring now to Fig. 8, wherein the operating mechanism for the creaser carrier 41' is shown with certain parts in spaced relation, this mechanism comprises among other elements the link 97' which carries the 60 65 70 75 80 85 90 95 100

actuating pin 99'; and this link has two bores to receive respectively the pin 93' and the pin 87'. In order to maintain the link 97' in telescoping relation with the pins 87', 93', the rear face of the 5 creaser carrier 41' contacts with the outer face of the link 97' as shown in Fig. 2. It may also be noted that the rear face of the slide 115 (Fig. 2) on the creaser carrier abuts the outer face of the horizontal bar of the cross 69' which is horizontally 10 slideable between flanges 115a and 115aa formed on the rear of the slide. This horizontal bar is shown again in Fig. 8. Thus the cover plate E holds the creaser carrier 41' in telescoping relation with the pivot pin 61' and the actuating 15 pin 99', and through the creaser carrier holds the link 97' in telescoping relation with the pins 87', 93'. It also acts through the creaser carrier 41' and the slide 115 to hold the cross 69' in place between the flanges formed on the back of 20 the slide.

The construction of the hammer carrier 41 is identical with that of the creaser carrier so far as this discussion is concerned. Referring to Fig. 3 the hammer carrier has a bore at its upper 25 end to receive a pivot pin 61 and another bore at its lower end to receive the actuating pin 99 and is held in place on said pins by the cover plate E which contacts with flat faces formed on bosses P, Q which are integral respectively with the upper and the lower portions of the hammer carrier 41. Referring to Fig. 6 which shows the hammer 30 operating mechanism with certain parts in spaced relation, the rear face of the hammer carrier 41 abuts against the outer face of the link 97 to hold that link in telescoping relation with two pins on the link 85; and the rear face of the slide 52 (Fig. 3) on the hammer carrier 41 abuts against the block 69 which is received between 35 horizontal flanges 52a and 52aa (Figs. 2 and 4) on the back of the slide. When, therefore, the cover plate has been removed, as shown in Fig. 3, the operator may remove both the creaser carrier 41' and the hammer carrier 41 by sliding them off their respective pins; and after these members 40 have been removed, he can remove various of the links shown in Figs. 6 and 8 by sliding them off the pins upon which they are mounted. There is thus provided a construction by which, after 45 the cover plate E has been removed, various parts of the operating mechanism of the machine may very readily be removed and replaced.

Although the invention has been set forth as embodied in a particular machine, it should be understood that the invention is not limited in 50 the scope of its application to the particular machine which has been shown and described.

Having thus described my invention, what I claim as new and desire to secure by Letters Patent of the United States is:

1. A machine of the class described having, in combination, means for feeding the work continuously, a folder, means for moving the folder across the line of feed movement of the edge of the work to form a fold in the margin of the moving work, and means for pressing the fold.

2. A machine of the class described having, in combination, means for feeding the work continuously, a folder, means for rocking the folder to form a fold in the margin of the moving work, and means for pressing the fold.

3. A machine of the class described having, in combination, means for feeding the work continuously and for pressing the fold, a folder for 75 forming the fold, and means for causing the

folder to move intermittently in the direction of feed movement of the work, and, during these intermittent movements, to move also in a direction at an angle to the direction of feed movement of the work.

4. A machine of the class described having, in combination, two feed members, means for causing said members to act in turn one after the other in such manner as to feed the work continuously, a folder, and means for moving the folder to form a fold in the margin of the work, one of said feed members acting as a fold presser.

5. A machine of the class described having, in combination, two feed members, means for moving said members in separate closed paths the 15 planes of which are parallel to the direction of feed movement of the work and for causing said members to act in turn one after the other to feed the work continuously, and a folder for forming a fold in the moving work, one of said 20 members acting as a fold-presser.

6. A machine of the class described having, in combination, two feed members, means for causing said members to act in turn one after the other to feed the work, a folder, and means for 25 moving the folder back and forth in the line of feed as well as in a path across the line of feed movement of the edge of the work, one of the feed members acting to press the fold formed by the folder.

7. A machine of the class described having, in combination, two feed members, means for causing said members to act in turn one after the other to feed the work continuously, a folder, and means for moving the folder back and forth 35 in the line of feed as well as across the line of feed, one of the feed members acting to press the fold formed by the folder.

8. A machine of the class described having, in combination, two pairs of feed members one member 40 of each pair engaging one side of the work and the other member engaging the other side, means for causing the two pairs to move in turn one after the other to feed the work, and a folder for forming a fold in the margin 45 of the work, one pair of feed members comprising a fold-presser.

9. A machine of the class described having, in combination, two pairs of feed members, means for causing the two pairs to act in turn 50 one pair after the other to feed the work, and a folder for forming a fold in the margin of the work, one pair of feed members comprising a creaser over the edge of which the margin of the work is bent by the folder, and the other 55 pair comprising a fold-presser.

10. A machine of the class described having, in combination, two pairs of feed members, one member of each pair engaging one side of the work and the other member the other side, means 60 for causing the two pairs to act in turn one after the other to feed the work continuously, a folder, and means for moving the folder back and forth in a path substantially parallel to the direction of feed movement of the work and for also moving 65 the folder across the line of feed movement of the edge of the work to form a fold, one pair of feed members comprising a fold-presser.

11. A machine of the class described having, in combination, two pairs of feed members, means 70 for causing the two pairs to act in turn one after the other to feed the work continuously, a folder, and means for moving the folder back and forth in a path substantially parallel to the direction of feed movement of the work and for also moving 75

the folder across the line of feed movement to form a fold, one pair of feed members comprising a creaser about the edge of which the margin of the work is bent by the folder, and the other pair comprising a fold-presser.

5 12. A machine of the class described having, in combination, means for feeding the work and pressing the fold, a folder for forming the fold, a carrier for the folder with respect to which the folder is movable, means for moving the folder with respect to the carrier, and means for moving the carrier up and down with respect to the plane in which the work is fed.

10 13. A machine of the class described having, in combination, means for feeding the work and pressing the fold, a folder for forming the fold, said folder being angularly movable, and means for causing the axis about which the folder is thus movable to move up and down with respect to the plane in which the work is fed.

15 14. A machine of the class described having, in combination, means for feeding the work and pressing the fold, a folder for forming the fold, said folder being angularly movable, and means for causing a point on the axis about which the folder is thus movable to travel in an orbital path lying in a plane at an angle to the edge of the work.

20 15. A machine of the class described having, in combination, means for feeding the work and for pressing the fold, a creaser to determine the line of fold, a cooperating folder for forming the fold by bending the margin of the work over the creaser, a carrier for the folder with respect to which the folder is angularly movable, means for causing the axis of angular movement of the folder to move in a predetermined path, and means for imparting angular movement to the folder.

25 16. A machine of the class described having, in combination, means for feeding the work and for pressing the fold, a creaser to determine the line of fold, a cooperating folder for forming the fold, a carrier for the folder with respect to which the folder is angularly movable, means for causing the axis of angular movement of the folder to move in an orbital path, and means for imparting angular movement to the folder.

30 17. A machine of the class described having, in combination, means for feeding the work and for pressing the fold, a folder, a carrier upon which the folder is angularly movable, and means for imparting bodily movement to the carrier in a direction across the line of feed and for imparting angular movement to the folder.

35 18. A machine of the class described having, in combination, means for feeding the work and for pressing the fold, a folder, a carrier upon which the folder is angularly movable about an axis substantially parallel to the line of feed, and means for imparting bodily movement to the carrier to shift the axis, for imparting angular movement to the folder and for moving the folder back and forth in a path substantially parallel to the direction of feed movement of the work.

40 19. A machine of the class described having, in combination, means for feeding the work and for pressing the fold, a folder, a carrier upon which the folder is pivoted, and means for raising and lowering the carrier and for swinging the folder about the pivot.

45 20. A machine of the class described having, in combination, means for feeding the work and for pressing the fold, a folder, a carrier upon which the folder is pivoted, and means for rais-

ing and lowering the carrier, for swinging the folder about the pivot and for moving the folder back and forth along the line of feed.

5 21. A machine of the class described having, in combination, a work support, means for feeding the work over said support and for pressing the fold, a folder, a carrier upon which the folder is pivoted, a frame upon which the carrier is movably mounted, and means for raising and lowering the frame thereby to vary the path of 10 movement of the folder with respect to the work support, for moving the carrier with respect to the frame and for rocking the folder about its pivot.

15 22. A machine of the class described having, in combination, means for feeding the work and for pressing the fold, a folder, a carrier upon which the folder is pivoted, a frame upon which the carrier is movably mounted, and means for raising and lowering the frame, for moving the 20 carrier with respect to the frame, for rocking the folder about its pivot and for moving the folder back and forth longitudinally of the axis of its pivot.

25 23. A machine of the class described having, in combination, a gage for bending up the margin of a piece of work fed past it, a folder, means for moving the folder to increase the bend in the margin to form a fold, a snipping cutter located 30 between the gage and the folder, and two members acting in turn one after the other to feed the work.

35 24. A machine of the class described having, in combination, a gage for bending up the margin of a piece of work fed past it, a folder, means for moving the folder to increase the bend in the margin to form a fold, a snipping cutter located between the gage and the folder, and two members acting in turn one after the other to feed the work, one of said members acting 40 also to press the fold.

45 25. A machine of the class described having, in combination, a gage for bending up the margin of a piece of work fed past it, said gage having at its forward end considered in the direction of feed movement of the work a substantially flat face extending at an angle to said direction, a snipping cutter adjacent to said face for snipping the bent-up margin, a folder located forwardly of the cutter, means for operating said 50 folder to increase the bend of the margin to form a fold, and two members acting in turn one after the other to feed the work, one of said members acting also to press the fold.

55 26. A machine of the class described having, in combination, means for feeding the work, for forming a fold in the margin thereof and for pressing the fold, and means moving intermittently with the work for snipping the margin thereof while the work is moving forward.

60 27. A machine of the class described having, in combination, means for feeding the work continuously, for forming a fold in the margin thereof and for pressing the fold, and means moving intermittently with the work for snipping the 65 margin thereof during such movement.

65 28. A machine of the class described having, in combination, means for feeding the work, for forming a fold in the margin thereof and for pressing the fold, a snipping cutter, and means for moving the cutter intermittently with the moving work and for operating the cutter to snip the margin of the work during these intermittent movements.

70 29. A machine of the class described having, in 75

- combination, work-feeding, work-guiding, fold-forming and fold-pressing instrumentalities, a snipping cutter movable intermittently in the direction of feed movement of the work, and 5 means for operating said cutter during said intermittent forward movements to snip the margin of the work.
30. A machine of the class described having, in combination, means for feeding the work continuously for forming a fold in the margin thereof and for pressing the fold, a cutter, and means for operating the cutter to snip the margin of the moving work.
31. A machine of the class described having, 15 in combination, two feed members, means for causing said members to act in turn one after the other to feed the work continuously, a cutter, means for operating the cutter to snip the margin of the moving work, and a folder, one of said feed members acting as a fold-presser.
32. A machine of the class described having, in combination, two feed members, means for causing said members to act in turn one after the other to feed the work continuously, a cutter, 25 means for moving the cutter back and forth in a path substantially parallel to the direction of feed movement of the work and in a path at an angle to said direction, and a folder, one of said members acting as a fold-presser.
- 30 33. A machine of the class described having, in combination, means for feeding the work, for forming a fold in the margin thereof and for pressing the fold, a snipping cutter, a carrier therefor upon which the cutter is movably 35 mounted, means for moving the carrier intermittently in a forward direction with the moving work, an actuator normally disconnected from the cutter-carrier, and means under the control of the operator for connecting the actuator with 40 the cutter-carrier to cause the cutter to snip the margin of the moving work.
34. A machine of the class described having, in combination, means for feeding the work, means for guiding the work and for forming a fold 45 in the margin thereof, means for moving the guiding and fold-forming means back and forth along the line of feed, and means for pressing the fold.
- 50 35. A machine of the class described having, in combination, means for feeding the work, a gage for facilitating the guiding of the work, a folder for forming a fold in the margin of the work, means for moving the gage and folder back and forth in the line of feed, and means for pressing the fold.
36. A machine of the class described having, in combination, means for feeding the work, a gage for facilitating the guiding of the work, a folder, 55 means for moving the folder transversely of the direction of feed movement to form a fold in the margin of the work, means for moving the gage and folder back and forth in the line of feed, and means for pressing the fold.
- 60 37. A machine of the class described having, in combination, means for feeding the work continuously, a gage for facilitating the guiding of the work, a folder for forming a fold in the margin of the work, means for moving the gage and folder back and forth in the line of feed, and means for pressing the fold.
- 70 38. A machine of the class described having, in combination, means for feeding the work continuously, a gage for facilitating the guiding of the work, a folder, means for moving the folder 75 transversely of the direction of feed movement to form a fold in the margin of the work, means for moving the gage and folder back and forth in the line of feed, and means for pressing the fold.
39. A machine of the class described having, in combination, means for feeding the work, a gage for bending up the margin of the work, a folder for increasing the bend to form a fold, means for pressing the fold, and means for moving the gage and the folder back and forth in paths substantially parallel to the direction of feed movement of the work.
40. A machine of the class described having, in combination, means for feeding the work continuously, a gage for bending up the margin of the work, a folder for increasing the bend to form a fold, means for pressing the fold, and means for moving the gage and the folder back and forth in paths substantially parallel to the direction of feed movement of the work.
41. A machine of the class described having, in combination, means for feeding the work, a gage for bending up the margin of the work, a folder, means for moving the folder in a path at an angle 25 to the direction of feed movement of the work for increasing the bend to form a fold, means for pressing the fold, and means for moving the gage and the folder back and forth in paths substantially parallel to the direction of feed movement of the work.
42. A machine of the class described having, in combination, means for feeding the work continuously, a gage for bending up the margin of the work, a folder, means for moving the folder in a path at an angle to the direction of feed movement of the work for increasing the bend to form a fold, means for pressing the fold, and means for moving the gage and the folder back and forth in paths substantially parallel to the direction of feed movement of the work.
43. A machine of the class described having, in combination, means for feeding the work, a combined gage and shear member for engaging and bending up the margin of the work, a cutter, 45 means for causing the cutter to cooperate with the gage and shear member to snip the margin of the work, means for moving the cutter and the combined member back and forth in paths substantially parallel to the direction of feed 50 movement of the work, a folder for forming a fold in the snipped margin, and means for pressing the fold.
44. A machine of the class described having, in combination, means for feeding the work continuously, a combined gage and shear member for engaging and bending up the margin of the work, a cutter, means for causing the cutter to cooperate with the gage and shear member to snip the margin of the work, means for moving the cutter and the combined member back and forth in paths substantially parallel to the direction of feed 55 movement of the work, a folder for forming a fold in the snipped margin, and means for pressing the fold.
45. A machine of the class described having, in combination, means for feeding the work, a combined gage and shear member for engaging and bending up the margin of the work, a cutter, means for causing the cutter to cooperate with the gage and shear member to snip the margin of the work, means for moving the cutter and the combined member back and forth in paths substantially parallel to the direction of feed movement of the work.

- ment of the work, a folder, means for moving the folder in a path at an angle to the direction of feed movement of the work to form a fold in the snipped margin, and means for pressing the fold.
46. A machine of the class described having, in combination, means for feeding the work continuously, a combined gage and shear member for engaging and bending up the margin of the work, a cutter, means for causing the cutter to cooperate with the gage and shear member to snip the margin of the work, means for moving the cutter and the combined member back and forth in paths substantially parallel to the direction of feed movement of the work, a folder, means for moving the folder in a path at an angle to the direction of feed movement of the work to form a fold in the snipped margin, and means for pressing the fold.
47. A machine of the class described having, in combination, means for feeding the work, a cutter for snipping the margin of the work, a folder for forming a fold in the snipped margin, means for moving the cutter and the folder forward intermittently with the work during the folding and cutting operations, and means for pressing the fold.
48. A machine of the class described having, in combination, means for feeding the work continuously, a cutter for snipping the margin of the work, a folder for forming a fold in the snipped margin, means for moving the cutter and the folder forward intermittently with the work during the folding and cutting operations, and means for pressing the fold.
49. A machine of the class described having, in combination, means for feeding the work, a gage for facilitating the guiding of the work, a cutter for snipping the margin of the work, a folder for forming a fold in the snipped margin, means for moving said gage, cutter and folder forward and back in paths substantially parallel to the direction of feed movement of the work, and means for pressing the fold.
50. A machine of the class described having, in combination, means for feeding the work continuously, a gage for facilitating the guiding of the work, a cutter for snipping the margin of the work, a folder for forming a fold in the snipped margin, means for moving said gage, cutter and folder forward and back in paths substantially parallel to the direction of feed movement of the work, and means for pressing the fold.
51. A machine of the class described having, in combination, means for feeding the work, a gage for engaging and bending up the margin of the work, a cutter for snipping the bent-up margin, a folder for forming a fold in the snipped margin, means for moving said gage, cutter and folder back and forth in paths substantially parallel to the direction of feed movement of the work, and means for pressing the fold.
52. A machine of the class described having, in combination, means for feeding the work continuously, a gage for engaging and bending up the margin of the work, a cutter for snipping the bent-up margin, a folder for forming a fold in the snipped margin, means for moving said gage, cutter and folder back and forth in paths substantially parallel to the direction of feed movement of the work, and means for pressing the fold.
53. A machine of the class described having, in combination, means for feeding the work, a gage for engaging and bending up the margin of the work, a cutter for snipping the bent-up margin,
- a folder movable in a path at an angle to the direction of feed movement of the work for forming a fold in the snipped margin, means for moving said gage, cutter and folder back and forth in paths substantially parallel to the direction of feed movement of the work, and means for pressing the fold.
54. A machine of the class described having, in combination, means for feeding the work continuously, a gage for engaging and bending up the margin of the work, a cutter for snipping the bent-up margin, a folder movable in a path at an angle to the direction of feed movement of the work for forming a fold in the snipped margin, means for moving said gage, cutter and folder back and forth in paths substantially parallel to the direction of feed movement of the work, and means for pressing the fold.
55. A machine of the class described having, in combination, a folder for forming a fold in the margin of a piece of work fed past it, two pairs of feed members, four mechanisms for operating the members, one member of one pair serving as a creaser and one member of the other pair as a fold-presser, and means for adjusting the four mechanisms simultaneously to vary the rate of feed of the work.
56. A machine of the class described having, in combination, a folder for forming a fold in a piece of work fed past it, two pairs of feed members, four mechanisms for operating the members to engage the work in turn one pair after the other and feed it, one member of one pair serving as a fold-presser and one member of the other pair serving as a creaser, four adjusting shafts, one for each mechanism, and means for adjusting the four shafts simultaneously to vary the rate of feed of the work.
57. A machine of the class described having, in combination, a folder for forming a fold in a piece of work fed past it, two pairs of feed members, four mechanisms for operating the members to engage the work in turn one pair after the other and feed it continuously, one member of one pair serving as a fold-presser and one member of the other pair serving as a creaser, four adjusting shafts, one for each mechanism, and means for adjusting the four shafts simultaneously to vary the rate of feed of the work.
58. A machine of the class described having, in combination, two feed members adapted to engage and release the work in turn one after the other to feed it, means for causing each member to move at increasing velocity as it engages the work, and the other member to move at decreasing velocity as it releases the work, said engagement and release being timed to cause the work to be fed continuously, and means for folding the margin of the work thus fed.
59. A machine of the class described having, in combination, means including two feed members adapted to engage and release the work in turn one after the other to feed it, means for moving each member in a closed path at a velocity which is increasing in some portions of the path and decreasing in others, means for causing each member to engage the work while the velocity of said member is increasing, means for causing the other member to release the work at substantially the same time while the velocity of said other member is decreasing whereby the work is fed continuously, and means for folding the margin of the work thus fed.
60. A machine of the class described having, in combination, means for feeding the work con-

tinuously, a folder, means for rocking the folder about an axis which is substantially parallel to the direction of feed movement to form the fold in the margin of the moving work, and means for pressing the fold.

61. A machine of the class described having, in combination, means for feeding the work continuously and for pressing the fold, a folder for forming the fold, and means for causing the folder to move intermittently in the direction of the feed movement of the work, and, during this intermittent movement, to move also in a path which extends across the line of feed movement of the edge of the work.

62. A machine of the class described having, in combination, means for feeding the work, a folder pivoted on an axis substantially parallel to the line of feed, means for moving the folder forward intermittently with the work, means for causing the folder to form a fold in the margin of the work while the work and the folder are moved forward, and means for pressing the fold.

63. A machine of the class described having, in combination, means for feeding the work continuously, a movable folder, means for actuating the folder to form a fold in the margin of the moving work, and means for pressing the fold.

64. A machine of the class described having, in combination, a plurality of feed members, means for causing the members to act in turn one after another to feed the work continuously, a movable folder, means for actuating the folder to form a fold in the margin of the moving work, and means for pressing the fold.

65. A machine of the class described having, in combination, a support for the work, means for feeding the work and for pressing the fold, a gage for bending up the margin of the work, a folder for engaging the bent-up margin and bending it over the body portion of the work to form a fold, a pivot for the folder, a carrier for the pivot, and means for raising and lowering the carrier with respect to the work support and for rocking the folder about its pivot.

66. A machine of the class described having, in combination, a frame, instrumentalities for forming a fold in the margin of a piece of work and for pressing the fold, certain of said instrumentalities being operative also to feed the work, mechanism located in the frame for operating certain of said instrumentalities, said mechanism including pivotally interconnected members having telescoping portions, and a member retained

against movement in a direction parallel to the axes of the pivots of said telescoping members for holding the telescoping portions of the members in telescoped relation.

67. A machine of the class described having, in combination, a frame, instrumentalities for feeding the work, for forming a fold in the margin thereof and for pressing the fold, mechanism located in an end of the frame for operating certain of the feeding and fold pressing instrumentalities, said mechanism including movable members having telescoping portions, and a plate fastened to the frame for holding the telescoping portions of the members in telescoped relation.

68. A machine of the class described having, in combination, an overhanging arm, means for feeding the work and for forming a fold in the margin thereof, a hammer for pressing the fold, mechanism located in the outer end of the arm for operating the hammer, said mechanism including members having telescoping portions, and a plate fastened to the outer end of the arm for holding the telescoping portions of the members in telescoped relation.

69. A machine of the class described having, in combination, an overhanging arm, feeding means, means for forming a fold in the margin of the work and for pressing the fold, mechanism located in the outer end of the arm for operating the feeding means, said mechanism including members having telescoping portions, and a plate fastened to the outer end of the arm for holding the telescoping portions of the members in telescoped relation.

70. A machine of the class described having, in combination, a carrier movable up and down with respect to the plane in which the work is fed, a folder for forming a fold pivoted on said carrier for movement about an axis substantially parallel to the line of feed, means for actuating said carrier and said folder, and means for feeding the work and pressing the fold.

71. A machine of the class described having, in combination, means for supporting and feeding a piece of work in a substantially horizontal plane, a carrier mounted for movement up and down toward and away from said plane, a folder for forming a fold mounted on said carrier for angular movement about an axis substantially parallel to the plane of movement of the work, means for moving the carrier up and down, and means for moving the folder about its axis.

WALTER E. NAUGLER.
